UNITED STATES PATENT OFFICE

2,070,690

AIR CONDITIONER

Rulo Wayne Smith, Auburn, Ind.

Application September 4, 1934, Serial No. 742,601

3 Claims. (Cl. 257—137)

The invention relates to air conditioners and it has for its object to provide a cheap, simple and efficient apparatus by which the temperature of the air in or supplied to a building or other enclosure may be lowered or altered.

Another object is to provide an air conditioning apparatus which, for its heat exchange, makes use of the water system in the building or structure where the apparatus is installed.

10 Another object is to provide an air conditioning apparatus in which a commercial automobile radiator forms the heat exchanging device in which water from the water system in the structure where the apparatus is installed is caused 15 to circulate and through the open spaces of which a draft of air is caused to travel.

Other objects and advantages will be set forth hereinbelow.

The invention consists of a low pressure radiator, a water supply connected to the radiator and circulating therein and a fan to cause air to travel through the open spaces in the radiator.

In the accompanying drawing

Figure 1 is a front view of a device embodying the invention, the louvres and most of the core being omitted.

Fig. 2 is a cross-section of the device.

Fig. 3 is a sectional elevation of a fraction of the radiator.

30 Fig. 4 is a side elevation of a modified form of the invention.

Fig. 5 is a side elevation of another modified form of the invention.

Fig. 6 is a side elevation of another modified form of the invention.

Referring to the illustrative embodiment of the invention, and first to Figs. 1 and 2, 1 is an open ended case in the forward portion of which is installed a low pressure radiator 2 that has a

40 high degree of heat transference and consisting of the core 3 and the upper tank 4 and lower tank 5, with both of which tanks the core communicates. A water connection 6 leads from the water system in the building where the device is installed, and is connected to the lower tank 5.

45 Preferably this connection 6 is extended upwardly in U form 7 so that its upper bend is located adjacent to or above the bottom of the upper tank 4. This extension is useful, when

50 hot water circulates in the core, to balance the pressure and assure the flow in the entire core. A waste line 27 is connected to the upper tank and leads to the drain or other point of discharge. The water circulates from the tank 5 upwardly through the zig zag tubes 9 of the core

(Fig. 3) and the corrugated fins 10 between the tubes transfer the temperature of the tubes to the air passing between the tubes and about the fins. A pan 11 is installed beneath the tank 5 to collect any condensation that may gather on the core and a conduit 12 may be connected to the pan to carry away such condensation, or the conduit 12 may be omitted and the pan may be removable for periodical emptying as preferred.

10 The core is formed of very thin metal so that its coefficient of heat transfer or exchange is high.

Louvres 13 may be installed in front of the radiator and may be adjusted to direct the air flow 15 as desired.

A baffle 14 is fixed in the case rearwardly of the radiator and extends entirely around the case. Rearwardly of the baffle is mounted an electric fan or blower 15 by which a draft of air 20 is forced through the radiator core and cooled by the walls of the tubes and the fins.

In Figs. 4 and 5 the case 16 is shorter than the case 1 and the fan or blower 15 is disposed outside the case. In order to direct the air 25 through the radiator I may attach a conduit 17 (Fig. 4) to the case, as by a draw string 18 and also attach it to the guard 19 of the fan by a similar string. In this embodiment the conduit may be formed of a suitable fabric. In Fig. 5 30 the conduit 20 is formed of rigid material and at its rear end is secured a resilient ring 21 against which the guard of the fan may abut.

In Fig. 6 I provide hooks 22 on the radiator carrying case 23 by which the case is attached to 35 the guard of the fan and an adjustable support 24 is provided at the bottom of the case by which the height of the case relatively to the fan is adjusted.

In all the views water from the water system 40 is circulated upwardly in the radiator core to cool or heat the core and a draft of air is forced through the openings or open spaces in the core to be cooled or heated by the core.

The device is portable and may be set up wherever there is a water supply and electrical current. It is most economical of construction and in operation.

What I claim is:

1. A device of the class described comprising 50 a radiator having a nest of vertical conduits and connecting fins, tanks connected to the opposite ends of the conduits respectively an inverted U-shaped conduit connected to the lower tank to supply a heat exchange medium under 55

pressure to the conduits, a discharge conduit connected to the upper tank, an electric fan rearwardly of the conduits and a conduit to direct the draft of air from the fan into contact with the nest of conduits and the fins.

- 5 2. A device of the class described comprising an open ended casing, a fluid circulating unit mounted in the casing and including upper and lower tanks and vertical tortuous water passages 10 connecting the tanks, a fluid discharge pipe connected to the upper tank, an inverted U-shaped fluid inlet conduit connected to the lower tank and having its bend above the plane of the bot-

tom of the upper tank and means to direct air under pressure past and in contact with the walls of the passages.

3. A device of the class described comprising an open front and back casing, a radiator mounted in the casing, means to cause a heat transfer agent to flow through the radiator, a fan adjacent to the casing and having a guard thereon and a resilient member engaged between the guard and the margin of the rear end of the 10 casing.

RULO WAYNE SMITH.
